MEDAL

Philip Leigh Barrager, Owatonna, Minn., assignor
to Josten Manufacturing Company, Owatonna,
Minn., a corporation of Minnesota

Application November 10, 1950, Serial No. 12,932

Term of patent 14 years

(Cl. D29—19)

To all whom it may concern:

Be it known that I, Philip Leigh Barrager, a citizen of the United States, residing at 148 East Broadway, Owatonna, State of Minnesota, have invented a new, original, and ornamental Design for Medal, of which the following is a specification, reference being had to the accompanying drawing, forming a part hereof.

The characteristic features of my design are shown in full lines in the drawing.

In the drawing:

Fig. 1 is an obverse view of a medal, showing my new design;

Fig. 2 is an edge view thereof.

Fig. 3 is a reverse view of Figure 1.

I claim:

The ornamental design for a medal, substantially as shown and described.

PHILIP LEIGH BARRAGER.
